UNITED STATES PATENT OFFICE.

RICHARD PEALE, OF ST. BENEDICT, PENNSYLVANIA, ASSIGNOR, BY MESNE ASSIGNMENTS, TO REMBRANDT PEALE, OF ST. BENEDICT, PENNSYLVANIA; W. SANDERS DAVIES, OF NEW YORK, N. Y.; AND WILLIAM S. WALLACE, OF PHILADELPHIA, PENNSYLVANIA.

MINING AND CONVEYING MACHINE.

Application filed June 9, 1919, Serial No. 302,929. Renewed January 12, 1927.

The invention relates to mining machines, and more particularly to mining machines adapted to undercut the coal and to convey away the coal after it is dislodged or broken away from the seam.

Objects and advantages of the invention will be set forth in part hereinafter, and in part will be obvious herefrom, or may be learned through practice with the invention; these objects and advantages being attained and realized through the means, instrumentalities, and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a top plan of a machine embodying the invention;

Fig. 2 is an elevation looking at Fig. 1 from the left, that is, looking at the back end of the machine;

Fig. 3 is an elevation, looking at Fig. 1 from the bottom, or at Fig. 2 from the right;

Fig. 4 is partially an elevation and partially a sectional view on line 4—4 of Fig. 1, and looking at Fig. 1 from the top, or at Fig. 2 from the left;

Fig. 5 is a fragmentary, sectional elevation, on an enlarged scale, on the line 5—5 of Fig. 1;

Fig. 6 is a fragmentary, vertical section, on an enlarged scale, on the line 6—6 of Fig. 1;

Fig. 7 is a fragmentary, horizontal section, on an enlarged scale, on line 7—7 of Fig. 2;

Fig. 8 is a fragmentary elevation of the left hand end of Fig. 3, somewhat diagrammatic in character, showing one arrangement of conveyors;

Fig. 9 is a diagrammatic elevation showing the machine in use in entry work;

Fig. 10 is a diagrammatic plan showing the machine used in room work;

Fig. 11 is a diagrammatic plan showing the machine used in narrow work, such as entry work;

Fig. 12 is a fragmentary, sectional figure, corresponding to the central part of Fig. 4; and

Fig. 13 is a detail view of the gearing connection between gear 12 and gear 13.

The invention provides a novel and useful machine adapted to make an undercutting, the machine sliding into the undercutting as it is made, and carrying into the undercutting conveying means adapted to underlie the greater part of the undercut coal. The undercut coal may then be broken down or suitably dislodged, as desired, subsequently to the completion of the undercutting and, falling upon the conveyor, is delivered outside of the machine.

The machine operating in this manner leaves it free, or as a matter of choice, to the workman as to the selection of the best means for breaking down the coal. In certain kinds of coal it is a great advantage both in speed of working and in the quality or size of the coal mined to simultaneously break down a relatively large mass of coal which has been previously undercut. The machine will also operate, where the nature of the coal admits, to break down the coal gradually or piecemeal as the undercutting proceeds, or to permit the coal to so break of itself, when it will do so, in any case conveying away the dislodged coal.

The machine is also provided with two cutting fronts, preferably at right angles to each other, and can travel and cut in two or more directions, that is, it will advance perpendicularly into the face of the coal and then along the face for an indefinite distance, the conveying means being capacitated to convey away the coal in either case.

The machine is of very low or flat construction whereby it can operate in very thin veins or seams and will in all practicable seams have sufficient head room over the machine for its easy and convenient attendance and control by the workman.

In the exemplary embodiment of this application, the machine includes as its main features a frame having cutter chains running in guides in its exterior face, the frame being preferably rectangular. It is of low or flat construction so that the greater part of the machine will slide into the undercutting as the cutters advance.

Supported in the frame, in such exemplary embodiment, is belt conveying mechanism, adapted to underlie a relatively large area of undercut coal, the coal when dislodged falling upon the conveyor and being carried away without manual handling. It is a great advantage to preliminarily undercut relatively large areas of the coal before the breaking down operation, for many reasons, such as reducing the breaking down effort, and saving the coal from excessive breakage and in connection therewith to convey the coal away without handling in small quantities or subjecting it to repeated handlings. More particularly, as embodied, the conveyor mechanism covers the greater part of the upper face of the frame which travels into the undercutting, and preferably a plurality of conveyors are employed one feeding or discharging on to another. Other features of the invention will be set forth in connection with the following detail description of the present embodiment.

Referring to the accompanying drawings, illustrating by way of example one embodiment of the invention, a frame 1 is provided which preferably serves as the main frame of the machine and also as the support and guideway for a cutter chain, constituting the preferred form of kerf cutting means. The relative dimensions of the machine are immaterial so far as concerns certain features of the invention, but for certain classes of work, such as entry driving or other narrow work, the frame is of a width such that the kerf cutter will undercut the entire width of the work, the machine in such case being driven or fed to the work in the forward direction only. The machine is also proportioned in such case so as to undercut to the most advantageous depth, the coal then being "shot down" or otherwise dislodged on to the conveyor. As embodied, the cutter chain 2 passes entirely about the exterior of the frame 1, running in a guideway 3 formed in the frame. While the machine requires relatively little handling or shifting, to facilitate the same, and for shipping it or moving it from one place of operation to another, and especially to so facilitate its handling in thin seams or veins, the frame is preferably made in two sections, which are preferably self contained, and are adapted to rest side by side on the mine bottom, and are fastened together so as to constitute a unit or integral mecha-

nism. As so constituted, one section or unit preferably contains the longitudinal conveyor and the other section or unit contains the cross or transverse conveyor and the motor. The placing of the sections side by side and fastening them together automatically connects the mechanisms of the two parts or sections so that they are driven from a common motor.

Referring more in detail to the drawings, the cutter driving means comprises two sprocket wheels 4 and 5, located preferably at the rear corners of the frame 1. These sprockets are horizontally arranged and their teeth 6 are in mesh with the links of the cutter chain 2, and their shafts 7 and 8 respectively, are journaled in bearings in the frame, as shown at 9 and 10 in Fig. 5.

The embodied form of driving means for the sprocket wheels 4 and 5 comprises connections from a single motor with slip mechanisms included to compensate for sudden variations in load or strain. Referring to the driving mechanism in detail, a pinion 12 is in mesh with teeth 12' formed on the undersurface of a crown gear 13 formed integrally with sprocket wheel 4. Pinion 12 is fixed on a shaft 14 journaled in bearings 15, 16 and 17 in one of the frame sections. In shaft 14 is provided a friction disc drive or connection 18 which may be of usual construction, having a spring 19 coiled about the shaft and working against a collar 20 on the shaft.

Referring to the drive for the other cutter chain driving sprocket wheel, a pinion 25 meshes with a crown gear 26 formed on the side of sprocket wheel 5. Pinion 25 is fixed on a shaft 27, which is journaled in bearings 28 and 29, supported on the frame or unit of the sectional frame. A friction disc device 30 is provided in the shaft 27 which may be of usual construction, and having a spring 31 coiled about the shaft and working against a collar 32 on the shaft.

Means are provided as embodied for driving the chain driving sprocket wheels together, when the frame is made in sections, by connecting their shafts to turn together. Shaft 27 is journaled in the inside reach 33 of its section of the frame with a squared end 34 projecting from the frame. Shaft 14 has an enlarged end 35 journaled in the inside reach of its section of the frame, the enlarged end 35 being socketed to receive the squared end 34 of shaft 27 when the two sections of the frame are fastened together side by side.

Means are provided for driving the cutter and the sprocket wheels and their shafts, and as embodied said means comprise a motor 40, having a pinion 41 fixed on its shaft. Pinion 41 meshes with an idler gear 42, journaled on a bearing 39, which idler gear meshes with a gear wheel 43, which gear

wheel is loose on the shaft 14. Fixed to the hub of gear wheel 43 is one member 44 of a clutch, the other member 45 of the clutch being splined and longitudinally slideable on shaft 14 in the usual manner. This clutch 5 simultaneously throws in or out both the sprocket wheels 4 and 5, each sprocket wheel having a friction or slip drive between it and the clutch, as already described. By throwing the clutch 44, 45 in or out, the cutter chain 2 may be driven or stopped, while each drive for the chain is protected against sudden strains by the respective slip drives 18 and 30.

15 Means are provided for feeding the machine to the work, and as embodied power driven devices are utilized to press the cutters against the coal and to slide the machine along the mine bottom as the kerf deepens. 20 For this purpose the machine is drawn along by two cables, and in the embodied arrangement jacks 46 and 47 are fastened in appropriate locations at the face of the work, and the cables 48 and 49 are made fast thereto 25 and are wound upon drums mounted upon and driven by the machine.

In the present machine, the drums 50 and 51 are driven from the motor 40, which also drives the cutter chain. A shaft 52 is journaled in bearings 53 and 54 on the machine frame, and fixed on this shaft 52 is a gear wheel 55, which gear wheel meshes with the gear wheel 43 on shaft 14. The two winding drums 50 and 51 are fixed to shaft 52 at 30 either end thereof, and the cables from the jacks 46 and 47 are wound upon these drums, respectively. The machine is preferably mounted on a plurality of shoe plates 56, the bottoms of which are round so that the machine will slide readily over the bottom in 35 any direction.

Guiding pulleys 57 and 58 are mounted on the machine frame at suitable points, for directing the pull of the cables on the machine. 45 As shown in Fig. 11, they are arranged to move the machine forwardly, as in entry work or other narrow work. They may be arranged, if desired, to drive or advance the machine sidewise, as might be required at 50 times in breast or room work, or in long wall work, or the like. With this mechanism constructed and arranged as described, the cutter chain and the advancing means for the machine are operated together and simultaneously from the common motor. It will 55 be noticed that the winding drums 50 and 51 and the pulley 57 are mounted on the rear raised portion of the frame at a substantial elevation above the pulley 58, which as 60 shown in Fig. 1, is mounted on the lower portion of the side of the frame in which the kerf cutter runs, so that the cable 49 will be raised substantially above the level of the conveyor 86. In some instances, where 65 it is necessary to give an increased clearance

of this cable 49 above the conveyor 86, the pulley 58 will project substantially above the top of the frame 1 in which it is mounted. It will be understood, of course, that these pulleys are replaceable and may be positioned wherever there is a corresponding socket in the frame. 70

Gear wheel 55 is preferably inclosed in a housing 60, which is formed in the top 61 of the casing, inclosing the motor, the sprocket wheels and other driving parts. All the operating mechanism is inclosed in a casing 62 to protect it from loose coal, and also from the dust so far as possible. The casing is formed by the top plate 61 fitting on the top edges of the frame, by the side frames and by a vertical wall 63 between the driving mechanism and the conveyor. 80

In the embodied form, a transversely arranged conveyor is arranged at the inside or toward the front of the machine, and in front of the motor and driving mechanism already described, upon which conveyor the dislodged coal falls and whereby it is passed across in front of the driving mechanism and then, by cooperating conveying means, alongside of the driving mechanism to the rear and to any desired or suitable loading mechanism or devices. 85

In such embodied mechanism, an endless conveyor 68 runs over an idle roller 69, located at the inner end of the conveyor and journaled in the machine frame. In the multiple unit or sectional machine, this conveyor extends entirely across its section and 90 discharges on to the longitudinal conveyor located in the other unit or section. At its opposite end conveyor 68 passes over a driving roller 70. This roller is preferably 95 driven from the common motor 40. 100

In the present embodied form, the shaft 71 of this roller is journaled in the machine frame, and is driven through pinions 82 and 83, and shaft 77 from a friction or slip drive 72 having a pressure spring 73, and a clutch 74 is provided for throwing the conveyor in or out. Shaft 77 is provided with suitable bearings 75 and 76. One disc member of friction drive 72 is splined on a shaft 77, and another disc of 74 is fast on a sleeve 78, which sleeve is loosely mounted on shaft 77. One member of clutch 74 is splined to slide on sleeve 78, and the other clutch member is fast on a bevel gear wheel 80, mounted loose on sleeve 78. The bevel gear 80 meshes with a bevel pinion 81 on the shaft of the motor 40. 115

As embodied, in the other section of the machine is mounted what may be termed the longitudinal conveyor, which conveys the dislodged coal to the rear, as already indicated. This conveyor 86 at its inner end runs over an idler roller 87, which is journaled in the machine frame, and at its outer end the conveyor runs over a driving roller 120 125 130

88, which is journaled in the machine frame. The shaft 89 of this driven roller has a squared end 90, extending from the frame plate 33 like the head 34. This squared head 90 fits into a socket in shaft 91 which is journaled in frame plate 36. When the two main frame sections are fitted together, the shafts will couple as shown in Fig. 1. Shaft 91 has preferably a friction or slip drive 92 and is provided with a bearing 94. Fixed to one part of this shaft 91 is a gear wheel 95, which is driven by a pinion 96 mounted on a shaft 97 journaled in bearings 98 and 99. Pinion 96 and shaft 97 are provided with a clutch 100 which connects and disconnects the pinion and shaft. Shaft 97 is shown as a continuation of the shaft of the common motor 40, which in this embodiment drives the entire machine. In this section of the machine also, a casing 101 is provided over the driving mechanism, with a vertical wall 102 closing it off from the conveyor (Fig. 5).

Suitable operating levers 103, 104 and 105 are provided for the clutches 45, 74 and 100, respectively, which levers project exteriorly from the casing to provide for the control of the clutches during the operation of the machine. The levers are pivoted on the machine frame and have yoked ends straddling the slidable clutch members in the usual manner, but are omitted from the drawing for clearness of showing.

In Fig. 5 a bridge plate 106^a is shown, upon which the coal is pushed from the conveyor over the top of the casing. This plate 106^a is anchored to the casing by bolts 106^b, and extends at its front edge substantially to the conveyor 86, to better enable the plate to scrape the coal from the conveyor 86: the only essential thing is that the plate should come down near the conveyor in order to remove the coal therefrom. In Fig. 8 an endless conveyor 106 is shown receiving the coal from the conveyor and adapted to transport or convey it to cars or other receiving devices in the rear.

In Fig. 9 the machine is shown in use in entry work in a thin coal seam, the bottom being "shot up" or excavated to give the requisite height or head room. The conveyor 106 is shown discharging into a car 107 standing on the track.

In Fig. 10 means are shown somewhat diagrammatically, in plan, for progressing the machine laterally or sidewise during the undercutting of the seam. The cables 48 and 49 from drums 50 and 51, are shown running respectively over pulleys 108 and 109, the cables being anchored to jacks 110 and 111. If desired, a fixed bearer cable or rail 112, running through rings or pulleys on the frame, may be used to hold the machine laterally in line. In Fig. 10, the pulley 58 has been detached from its socket,

and the pulley 108 has been positioned so that the cable 49 passes from the pulley 57 which is in a raised elevation, downwardly to the pulley 108 and thence to the jack 110. As hereinbefore stated, this pulley 108, if desired, may project upwardly a slight distance above the level of the frame 1 so as to give additional clearance to permit the coal to pass on the conveyor beneath the cable 49.

Plates 113 are employed to direct the coal on to the conveyors, and horizontally disposed supporting plates 114 are preferably located closely beneath the top reaches of the conveyors, respectively, and are fixed to and supported by the machine frame. These plates enable the conveyors to receive the impact of the dislodged and falling coal without dislocation, deformation, or other damage, although the impact is not severe or serious in relatively thin seams.

A bridge plate 115 carries the traveling coal from the transverse conveyor 68 on to the longitudinal conveyor 86. This bridge plate is preferably provided with means for assisting in holding the machine sections together, and the embodied form of such holding means comprises pins 116 fixed to the bottom of the bridge plate, and fitting into holes formed in the top of the abutting reaches 33 and 36 of the frames of the sections.

Additional means for holding the sections together are shown as comprising a latch 117, pivoted on one section of the frame, and taking over a lug 118 on the other section of the frame 1, a pin 119 fitting into a hole in the frame to lock the holding means in engagement.

The manner of operation of the machine will be understood from the descriptions given in connection with the various devices and mechanisms. As previously pointed out, the machine can remain continuously at the face of the work, the undercut coal being "shot down" or otherwise dislodged on to the conveyors, and is at once conveyed across and back from the machine into the cars or other receiving means, and all moving of machines and substitution of one machine for another is avoided. This is the case whether the machine be employed in entry driving or other narrow work, or in room work or other wide work.

The invention in its broaded aspects is not limited to the detailed constructions and arrangements shown and described herein, but changes may be made therefrom without departing from the principles of the invention and without sacrificing its chief advantages.

What I claim is:

1. A mining machine including in combination a frame adapted to rest upon the mine bottom and to enter the kerf as it is

cut, a kerf cutter running in the exterior of said frame, and an endless belt conveyor within the frame and entirely below the top of the cut kerf.

5 2. A mining machine including in combination a frame adapted to rest upon the mine bottom and to enter the kerf as it is cut, an endless kerf cutter running in the exterior of said frame, an endless belt conveyor within the frame, and entirely below the top of the cut kerf, and a motor for driving the conveyor, located within the reaches of the kerf cutter.

15 3. A mining machine including in combination a frame, a kerf cutter running in the exterior of said frame, a conveyor within the frame and entirely below the top of the cut kerf, and means for driving the kerf cutter and the conveyor together or independently.

20 4. A mining machine including in combination a frame, a kerf cutter running in the exterior of said frame, an endless belt conveyor within the frame, and entirely below the top of the cut kerf, and a motor located within said frame, for driving the kerf cutter and the endless belt conveyor.

25 5. A mining machine including in combination a frame an endless kerf cutter running entirely about the frame, and adapted to enter the kerf as it is cut, an endless belt conveyor located wholly within the confines of said frame and positionable in the cut kerf for receiving the coal directly after it is dislodged, and a motor located within the frame for driving the kerf cutter and the conveyor.

30 6. A mining machine including in combination a frame, a kerf cutter running entirely about the frame, and an endless belt conveyor entirely within the frame.

35 7. A mining machine including in combination a frame, an endless kerf cutter running entirely about the frame, a plurality of endless belt conveyors entirely within the frame and on substantially the same level as the kerf cutter, whereby both conveyors are positionable in the cut kerf, and means for driving the conveyor.

40 8. A mining machine including in combination a frame adapted to rest upon the mine bottom, a kerf cutter running in the exterior of said frame, and a plurality of conveyors entirely within the frame, one of the conveyors discharging on to another conveyor.

45 9. A mining machine including in combination a frame adapted to rest upon the mine bottom, a kerf cutter running in the exterior of said frame, and a plurality of endless conveyors within the frame, one of the conveyors discharging on to another conveyor.

50 10. A mining machine including in combination a frame adapted to rest upon the mine bottom and adapted to enter the kerf, a kerf cutter running in the exterior of said

frame, a conveyor entirely within the frame and entirely below the level of the top of the cut kerf, a motor within the frame, and separate driving connections therefrom to the kerf and to the conveyor.

70 11. A mining machine including in combination a frame adapted to rest upon the mine bottom and adapted to enter the kerf, a kerf cutter running in the exterior of said frame, a conveyor entirely within the frame and entirely below the top of the cut kerf, a motor within the frame, separate driving connections therefrom to the kerf cutter and to the conveyor, and clutches in the respective driving connections.

75 12. A mining machine including in combination a frame, an endless kerf cutter running entirely about the frame, a plurality of conveyors within the frame and within the reaches of the endless kerf cutter, one of the conveyors discharging on to another conveyor and a motor within the frame and within the reaches of the kerf cutter, for driving the conveyors.

80 13. A mining machine including in combination a frame adapted to rest upon the mine bottom, a kerf cutter running in the exterior of said frame, and a plurality of endless belt conveyors within the frame and transversely arranged with respect to each other.

85 14. A mining machine including in combination a frame adapted to rest upon the mine bottom, an endless kerf cutter running in the exterior of said frame, a plurality of conveyors within the frame and within the reaches of the kerf cutter, the conveyors being transversely arranged, with one conveyor discharging onto the other, and a motor within the frame, and within the reaches of the kerf cutter, for driving the conveyors.

90 15. A mining machine including in combination a frame, a kerf cutter running entirely about the frame, and a plurality of conveyors entirely within the frame and transversely arranged with respect to each other.

95 16. A mining machine including in combination a frame, an endless kerf cutter running entirely about the frame, a plurality of endless belt conveyors within the frame, one conveyor discharging on to another the conveyors being within the frame and within the reaches of the kerf cutter, and a motor within the frame and within the reaches of the kerf cutter, for driving the kerf cutter and the conveyors.

100 17. A mining machine including in combination a sectional detachable frame, and a kerf cutter running entirely about the frame and a conveyor carried by each section of the frame.

105 18. A mining machine including in combination a sectional detachable frame adapted to rest upon the mine bottom with the sections side by side, means for fastening the

sections together, and a kerf cutter running entirely about the frame.

19. A mining machine including in combination a sectional detachable frame adapted to rest upon the mine bottom with the sections side by side, a kerf cutter, and a motor in one of said sections, a conveyor in the other section, and driving connections therebetween.

10 20. A mining machine including in combination a sectional detachable frame adapted to rest upon the mine bottom with the sections side by side, a kerf cutter, and a conveyor within the frame, entirely below the 15 top of the cut kerf.

21. A mining machine including in combination a sectional detachable frame adapted to rest upon the mine bottom with the sections side by side, a kerf cutter, and a conveyor entirely within each section of the 20 frame.

22. A mining machine including in combination a sectional detachable frame adapted to rest upon the mine bottom with the sections side by side, a kerf cutter, and a conveyor in each section of the frame, one of the conveyors discharging on to another of 25 said conveyors.

23. A mining machine including in combination a sectional detachable frame adapted to rest upon the mine bottom with the sections side by side, a kerf cutter running entirely about the frame, and a conveyor entirely within the frame.

30 24. A mining machine including in combination a sectional detachable frame adapted to rest upon the mine bottom with the sections side by side, a kerf cutter running entirely about the frame, and a conveyor within 35 each section of the frame, one conveyor discharging on to another of said conveyors.

25 25. A mining machine including in combination a sectional detachable frame adapted to rest upon the mine bottom with the sections side by side, a kerf cutter, and a conveyor in each section of the frame, a motor within one section of the frame driving the kerf cutter and the conveyors.

30 26. A mining machine including in combination a sectional detachable frame adapted to rest upon the mine bottom with the sections side by side, and a kerf cutter running entirely about the frame, conveyors within said frame, a motor within one section of the frame driving the kerf cutter and the conveyors.

35 27. A mining machine including in combination a frame, a kerf cutter extending about the frame, and two conveyors within the frame running transversely to each other, and one conveyor discharging on to the other at the inner end thereof.

40 28. A mining machine including in combination a frame, a kerf cutter extending about the frame, and two conveyors within 45

the frame running transversely to each other, and one conveyor discharging on to the other at the inner end thereof, a motor within the frame and independently operable connections for driving the kerf cutter 70 and the conveyors.

29. A mining machine including in combination a frame adapted to rest upon the mine bottom, a kerf cutter running in the edges of the frame, means for driving the frame to the work, a conveyor running longitudinally of the frame at one side thereof, a conveyor running across the frame at the front thereof and discharging on to the inner end of the longitudinal conveyor. 75 80

30. A mining machine including in combination a frame adapted to rest upon the mine bottom, a kerf cutter running in the edges of the frame, means for driving the frame to the work, a conveyor running longitudinally of the frame at one side thereof, a conveyor running across the frame at the front thereof and discharging on to the inner end of the longitudinal conveyor and a motor within the frame outside the transverse conveyor for driving the conveyors and kerf cutter. 85 90

31. A mining machine including in combination a frame adapted for the greater part of its length to pass into an undercut kerf, a cutter chain running in the outside of said frame to cut a kerf into which the frame slides, and belt conveyor means co-extensive with the inner area of that portion of the frame intended to pass into the kerf, and adapted to receive the entire mass of undercut coal in case it is dislodged at one time. 95 100

32. A mining machine including in combination a frame adapted for the greater part of its length to pass into an undercut kerf, a cutter chain running the outside of said frame to cut a kerf into which the frame slides, and a plurality of belt conveyors filling the greater part of the frame intended to pass into the kerf, said conveyors being adapted to receive the entire mass of undercut coal in case it is dislodged at one time, one of said conveyors discharging onto another. 105 110 115

33. A mining machine including in combination a frame adapted to move over the mine bottom and pass into an undercut kerf, a cutter chain running about at least two of the exterior sides of the frame to cut the kerf, the machine being adapted to advance with either of said two sides as the cutting front, and means for advancing the machine in either of said two directions and two conveyors mounted within the frame, one being arranged to withdraw the cut coal from one side when it functions as the cutting front, and the other being arranged to withdraw the coal from the other side when it functions as the cutting front. 120 125 130

34. A mining machine including in combination a frame adapted to move over the mine bottom and pass into an undercut kerf, a cutter chain running about at least two of the exterior sides of the frame to cut the kerf, the machine being adapted to advance with either of said two sides as the cutting front, and means for advancing the machine in either of said two directions, and a plurality of conveyors within said frame and arranged transversely to each other.
35. A mining machine including in combination a frame adapted to move over the

mine bottom and pass into an undercut kerf, a cutter chain running about at least two of the exterior sides of the frame to cut the kerf, the machine being adapted to advance with either of said two sides as the cutting front, and means for advancing the machine in either of said two directions, and a plurality of conveyors within said frame and arranged at right angles to each other.

In testimony whereof, I have signed my name to this specification.

RICHARD PEALE.
